(57) **CLAIM**

The ornamental design for a astronomical telescope as shown and described.

DESCRIPTION

FIG. 1 is a front, top, right perspective view of an astronomical telescope showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, top, left perspective view thereof, showing the article in a state of use;

FIG. 9 is a rear, bottom, right perspective view thereof, showing the article in a state of use;

FIG. 10 is an enlarged portion view taken from encircled portion labeled, “10,” in FIG. 2;

FIG. 11 is an enlarged portion view taken from encircled portion labeled, “11,” in FIG. 4;

FIG. 12 is an enlarged portion view taken from encircled portion labeled, “12,” in FIG. 5; and,

FIG. 13 is an enlarged portion view taken from encircled portion labeled, “13,” in FIG. 7.

The dashed-dot lines form the boundary of the enlarged portion views of FIGS. 10-13 in FIGS. 2, 4, 5, and 7 and form no part of the claimed design. The even dashed broken lines shown in the drawings are included for the purpose of illustrating portions of the astronomical telescope that form no part of the claimed design.
